UNITED STATES PATENT OFFICE

FRANK E. BESSLER, OF AKRON, OHIO, ASSIGNOR TO THE BESSLER DISAPPEARING STAIRWAY COMPANY, OF AKRON, OHIO, A CORPORATION OF OHIO

DISAPPEARING STAIRWAY

Application filed March 11, 1929. Serial No. 345,928.

This invention relates to disappearing stairways of that type cooperating with a ceiling opening between lower and upper floors of a building.

The general purpose of the invention is to provide a disappearing stairway of a simple, inexpensive type, which will be easily and safely operable by hand and which may dispense with the usual cable connections and 10 spring or power operated drums heretofore employed in disappearing stairway construction.

The foregoing and other purposes of the invention are attained in the disappearing 15 stairway shown in the accompanying drawings and described below. It is to be understood that the invention is not limited to the specific forms thereof shown and described.

Of the accompanying drawings, Figure 1, 20 is a side elevation partly in section of a stairway installation, embodying the invention with the stairway shown in its retracted position on the upper floor;

Figure 2 is a side elevation partly broken 25 away and in section and shows said stairway swung downwardly into the position assumed thereby after the first operation of extending it toward its position of use;

Figure 3 is a similar side elevation showing 30 the stairway completely extended to the lower floor;

Figure 4 is a front elevation thereof;

Figures 5 and 6 are detail side elevations 35 of the device for locking the stair structure onto its mount and showing respectively the operation of unlocking and relocking the stair structure;

Figure 7 is a detail section on line 7—7 of 40 Figure 2 illustrating the construction whereby the toggle holding the panel open is broken to permit the panel to shut when the stairway is swung upwardly toward its retracted position;

Figure 8 is plan of another disappearing 45 stairway installation embodying the invention shown in its retracted position on the upper floor;

Figure 9 is a side elevation partly in section of the upper part of the above stairway

installation when extended to its position of use; and

Figure 10 is a front elevation thereof.

Referring to Figures 1 to 7 of the drawings the numeral 11 designates a suitable 55 opening in a ceiling between lower and upper floors of a building and a panel 12 is shown hinged to one side of said opening to close the same when the stairway is not in use.

A suitable stair structure 13 is slidably mounted on a support 14 through the agency of bars 14^a mounted on brackets 14^b and arms 31 secured to the support 14, which bars co-operate with grooves 15 running along the 65 outer sides of the stairway stringers. The support 14 is pivoted to one end of the opening 11 which permits the lower end of the stairway to be swung down through the opening 11 (see Figures 1 and 2) and then slid 70 downwardly on bars 14^a whereby the stair is extended to the lower floor (Figure 3).

The stair structure 13 is arranged normally to be locked to the support 14 in its retracted state by provision of a cam lock 17 75 pivoted at 18 on the outer side of one stairway stringer. The lock 17 is provided with a hook portion 19 adapted to engage about a stud 20 on one of the brackets 14^b to hold the stairway against sliding downwardly as it is 80 swung through opening 11. A cam face 21 on the lock 17 is arranged to be moved against stud 20 by sliding the stair structure upwardly slightly on support 14 to swing the hook portion 19 to such a position (See Figure 5) 85

that when the stair structure is then drawn downwardly the stud 20 will engage a cam edge 22 below the hook portion and swing the cam lock upwardly out of the way permitting the stairway to be extended to the lower floor. 90

The cam face 21 terminates in a stop 21^a preventing more than a slight upward unlocking movement. A cam edge 23 is arranged on the lock so as to be projected downwardly as the hook portion 19 is swung upwardly whereby when the stairway is to be relocked an upward movement of the stair structure engages said cam edge with stud 20, causing the hook portion 19 to be swung 95 downwardly (Figure 6) whereupon upon re-

- lease of the stair structure, it will move downwardly, stud 20 in effect passing through a groove 24 in back or above the cam face 21 into reengagement with hook portion 19. The pivot of lock 17 is constructed in any suitable way so that frictional resistance therein will hold the lock in any position to which it is moved against the action of gravity thereon.
- 10 The stair structure 13 is connected to the panel 12 to be partly operated thereby, as hereinafter explained, and also to hold the panel open when the stairway is extended, by means of an adjustable toggle linkage 25, the ends of which are pivoted respectively at 26 and 27 on brackets 28 and 29, swiveled onto panel 12 and onto a channel member 30 connected to the support 14, whereby the toggle may twist in such a way that one end 20 may move in the arc described by the panel in opening and closing and the other in the arc described by the stair structure as it is swung through the opening, these arcs being in planes at right angles to each other. The 25 channel member 30 has one arm 30^a so arranged as to engage and break the toggle as the stair structure is swung upwardly to permit the panel to close (Figure 7).
- 15 A spring control device may be provided 30 on the stair structure comprising arm 31, secured to the support 14 and connected by a spring 32 to one end of a lever 33 pivoted in the opening at 34 and the other end of which 35 is adapted to engage the end wall of the opening so as to apply yielding resistance to further downward swinging movement of the stair structure after its lower end has been pulled through the opening by the toggle 25 when the panel is opened.
- 20 For operating the stairway from below, the panel 12 is provided with a chain 36 to pull it down out of opening 11, it being normally urged shut by springs 37, 37 connected at one end adjacent to the free edge of the 25 panel and at the other to the side wall opening 11 above the panel hinges. For operating the stairway from above, the upper face of the panel is provided with a diagonally arranged rail 38, adapted to be engaged by one 30 side of the lower portion of the stair structure, when the upper end thereof is lifted from the upper floor to push the panel downwardly as indicated in dotted lines in Figure 1 until toggle 25 is extended to hold the panel down.
- 25 In operation of this form of the invention to extend the stairway to its position of use, either the chain 36 is pulled from below or the upper end of the stair structure is lifted from above to swing the panel downwardly, movement of the panel to its fully opened position causing the stair structure to swing downwardly through the opening by means of the toggle connection 25 between the panel and the support 14. The arrangement of the toggle 25 between the support 14 and the panel is such as to lock the panel 12 in fully-opened position. When the stairway is operated from the upper floor, the upper end of the stair structure is lifted and the panel is opened by engagement of one side of the lower end of the stairway with rail 38. The stairway, which is now in position so that it may be grasped either from the lower or upper floors, is then slid upwardly slightly and then downwardly on support 14 to release cam lock 17 whereupon it is slid and swung downwardly to the lower floor, swinging thereof being retarded by spring 32 and downward movement being retarded by spring drum 40.
- 30 To retract the stairway, the stair structure is moved upwardly until cam lock 17 re-engages and locks the same on stud 20 of the support 14. It is then swung upwardly, toggle 25, during the initial part of this movement, twisting on the swivel mountings so that one member thereof engages arm 30^a of channel 30 which causes said toggle to be broken and permits panel 12 to be closed by springs 37 as the stair structure swings by gravity to its retracted position, the upper end of the stair structure being longer than and slightly overbalancing the lower end thereof and the support 14 when the stair structure is locked to the support 14.
- 35 The form of stairway shown in Figures 8 to 10 is quite similar to that described above excepting that the panel closure is arranged to be operable by the stair structure either from above or below and in this type of construction the closure is preferably made in double panel form, each panel 12^a being hinged to the opposite sides of the opening 11^a and normally urged shut by springs 37^a. Diagonal rails 38^a, 38^b are arranged on the panels 12^a so as to be engaged by the opposite sides of the stair structure to swing the panels open when operated either from above or below, operation from below being arranged for by provision of a chain 36^a connected to the stair structure and extended down between the meeting edges of the panels. The construction and operation of this form of the invention is otherwise similar to the first form described with the exception, of course, that toggle 25 is not required, as the weight of the panels is considerably less in this construction and in view of the fact that the operating chain is connected to the stairs and not to the panel.
- 40 In order to assist in the operation of either form of the above described stairways, either may be counter-balanced by a spring drum 40 mounted on a pair of cross bars 41 on the support 14 and on which is wound a tape 42 connected to the stair structure at 43. A standard form of sash balance is suitable for this purpose.
- 45 It will be apparent from the foregoing 100

that a simple inexpensive and safely operable stairway has been provided by the invention. Modifications other than those disclosed herein obviously may be adopted without departing from the spirit of the invention or the scope of the appended claims.

What is claimed is:—

1. A disappearing stairway for cooperation with an opening in a ceiling between lower and upper floors of a building including arms pivoted at one end of the opening, a stair structure slidably mounted on said arms, means for locking said stair structure in a retracted position on said arms, said locking means being adapted to be released or relocked by a reciprocating movement of the stair structure, the upper portion of said stair structure slightly over-balancing the lower portion thereof when retracted on the arms to hold the stairway in its retracted position above the opening, a panel hinged at one side of the opening, yielding means tending to hold the panel shut, means for pulling the panel downwardly from below, a rail diagonally directed across the upper side of the panel adapted to be engaged by one side of the lower portion of the stair structure to open the panel from above, toggle means between the panel and stair structure for swinging the lower end of the stair structure through the opening as the panel is opened from below and adapted to lock the panel open, said toggle means having swiveled connections with the stair structure and panel permitting its ends to follow the respective arcs through which the panel and stair structure swing, means in contact with which one member of the toggle is adapted to twist to break the toggle as the stair structure is swung upwardly through the opening to permit the panel to close.

2. A disappearing stairway for cooperation with an opening in a ceiling between lower and upper floors of a building including arms pivoted at one end of the opening, a stair structure slidably mounted on said arms, means for releasably locking said stair structure in a retracted position on said arms, means for pulling the panel downwardly from below, a rail diagonally directed across the upper side of the panel adapted to be engaged by one side of the lower portion of the stair structure to open the panel from above, toggle means between the panel and stair structure for swinging the lower end of the stair structure through the opening as the panel is opened from below and adapted to lock the panel open, said toggle means having swiveled connections with the stair structure and panel permitting its ends to follow the respective arcs through which the panel and stair structure swing, means in contact with which one member of the toggle is adapted to twist to break the toggle as the stair structure is swung upwardly through the opening to permit the panel to close.

3. A disappearing stairway for cooperation with an opening in a ceiling between lower and upper floors of a building including arms pivoted at one end of the opening, a stair structure slidably mounted on said arms, means for locking said stair structure in a retracted position on said arms, said locking means being adapted to be released or relocked by a reciprocating movement of the stair structure, the upper portion of said stair structure slightly overbalancing the lower portion thereof when retracted on the arms to hold the stairway in its retracted position above the opening, a panel hinged at one side of the opening, yielding means tending to hold the panel shut, means for pulling the panel downwardly from below, a rail diagonally directed across the upper side of the panel adapted to be engaged by one side of the lower portion of the stair structure to open the panel from above, toggle means between the panel and stair structure for swinging the lower end of the stair structure through the opening as the panel is opened from below and adapted to lock the panel open, said toggle means having swiveled connections with the stair structure and panel permitting its ends to follow the respective arcs through which the panel and stair structure swing, means in contact with which one member of the toggle is adapted to twist to break the toggle as the stair structure is swung upwardly through the opening to permit the panel to close, and yielding means resisting further downward swinging of the stair structure after it has been initially swung downwardly by said toggle means.

4. A disappearing stairway for cooperation with an opening in a ceiling between lower and upper floors of a building including arms pivoted at one end of the opening, a stair structure slidably mounted on said arms, means for releasably locking said stair structure in a retracted position on said arms, means for pulling the panel downwardly from below, a rail diagonally directed across the upper side of the panel adapted to be engaged by one side of the lower portion of the stair structure to open the panel from above, toggle means between the panel and stair structure for swinging the lower end of the stair structure through the opening as the panel is opened from below and adapted to lock the panel open, said toggle means having swiveled connections with the stair structure and panel permitting its end to follow the respective arcs through which the panel and stair structure swing, and means in contact with which one member of the toggle is adapted to twist to break the toggle as the panel is opened from above, toggle means be-

tween the panel and stair structure for swinging the lower end of the stair structure through the opening as the panel is opened from below and adapted to lock the panel open, said toggle means having swiveled connections with the stair structure and panel permitting its ends to follow the respective arcs through which the panel and stair structure swing, means in contact with which one member of the toggle is adapted to twist to break the toggle as the stair structure is swung upwardly through the opening to permit the panel to close.

5. A disappearing stairway for cooperation with an opening in a ceiling between lower and upper floors of a building including arms pivoted at one end of the opening, a stair structure slidably mounted on said arms, means for releasably locking said stair structure in a retracted position on said arms, means for pulling the panel downwardly from below, a rail diagonally directed across the upper side of the panel adapted to be engaged by one side of the lower portion of the stair structure to open the panel from above, toggle means between the panel and stair structure for swinging the lower end of the stair structure through the opening as the panel is opened from below and adapted to lock the panel open, said toggle means having swiveled connections with the stair structure and panel permitting its ends to follow the respective arcs through which the panel and stair structure swing, means in contact with which one member of the toggle is adapted to twist to break the toggle as the stair structure is swung upwardly through the opening to permit the panel to close, and yielding means resisting further downward swinging of the stair structure after it has been initially swung downwardly by said toggle means.

6. A disappearing stairway for cooperation with an opening in a ceiling between lower and upper floors of a building including arms pivoted at one end of the opening, a stair structure slidably mounted on said arms, means for locking said stair structure in a retracted position on said arms, said locking means being adapted to be released or relocked by a reciprocating movement of the stair structure, the upper portion of said stair structure slightly overbalancing the lower portion thereof when retracted on the arms to hold the stairway in its retracted position above the opening, a panel hinged at one side of the opening, yielding means tending to hold the panel shut, means for pulling the panel downwardly from below, a rail diagonally directed across the upper side of the panel adapted to be engaged by one side of the lower portion of the stair structure to open the panel from above, toggle means between the panel and stair structure for swinging the lower end of the stair structure through the opening as the panel is opened from below and adapted to lock the panel open, said toggle means having swiveled connections with the stair structure and panel permitting its ends to follow the respective arcs through which the panel and stair structure swing, and means in contact with which one member of the toggle is adapted to twist to break the toggle as the panel is opened from above, toggle means be-

the stair structure is swung upwardly through the opening to permit the panel to close.

5. A disappearing stairway for cooperation with an opening in a ceiling between lower and upper floors of a building including arms pivoted at one end of the opening, a stair structure slidably mounted on said arms for releasably locking said stair structure in a retracted position on said arms,

means for pulling the panel downwardly from below, toggle means between the panel and stair structure for swinging the lower end of the stair structure through the opening as the panel is opened from below and adapted to lock the panel open, said toggle means having swiveled connections with the stair structure and panel permitting its end to follow the respective arcs through which the panel

20 and stair structure swing, and means in contact with which one member of the toggle is adapted to twist to break the toggle as the stair structure is swung upwardly through the opening to permit the panel to close.

25 6. A disappearing stairway for cooperation with an opening in a ceiling between lower and upper floors of a building including arms pivoted at one end of the opening, a stair structure slidably mounted on said arms, means for releasably locking said stair

30 structure in a retracted position on said arms, means for pulling the panel downwardly from below, and means between the panel and stair structure for swinging the lower end of the stair structure through the opening as the panel is opened from below and adapted to lock the panel open.

7. A disappearing stairway for cooperation with an opening in a ceiling between lower and upper floors of a building including arms pivoted at one end of the opening, a stair structure slidably mounted on said arms, means for locking said stair structure in a retracted position on said arms, said

45 locking means being adapted to be released or relocked by a reciprocating movement of the stair structure, the upper portion of said stair structure slightly overbalancing the lower portion thereof when retracted on the arms to hold the stairway in its retracted position above the opening, a panel hinged at one side of the opening, and yielding means tending to hold the panel shut.

8. A disappearing stairway for cooperation with an opening in a ceiling between lower and upper floors of a building including arms pivoted at one end of the opening, a stair structure slidably mounted on said arms, means for releasably locking said stair structure in a retracted position on said arms, a hinged panel for closing said opening, and a rail diagonally directed across the upper side of the panel adapted to be engaged by one side of the lower portion of the stair structure to open the panel from above.

9. The combination with a ceiling opening between lower and upper floors of a building of a stair structure pivotally and slidably mounted at one end of the opening, a panel closure for the opening hinged at one side of the opening whereby its plane of swinging movement is at right angles to the plane of swinging movement of the stair structure, means normally urging the panel shut, said panel being adapted to be pushed open by swinging the stair structure downwardly, yielding means for resisting further downward swinging of the stair structure after the panel is open, and means for releasably locking the stair structure against sliding on its mounting.

10. The combination with a ceiling opening between lower and upper floors of a building, of a stair structure pivotally and slidably mounted at one end of the opening, a panel closure for the opening hinged at a side of the opening whereby its plane of swinging movement is at right angles to the plane of swinging movement of the stair structure, means normally urging the panel shut, said panel being adapted to be pushed open by swinging the stair structure downwardly, and means for releasably locking the stair structure against sliding on its mounting.

11. The combination with a ceiling opening between lower and upper floors of a building of a stair structure pivotally and slidably mounted at one end of the opening, a panel closure for the opening hinged at a side of the opening whereby its plane of swinging movement is at right angles to the plane of swinging movement of the stair structure, means normally urging the panel shut, said panel being adapted to be pushed open by swinging the stair structure downwardly, and yielding means for resisting further downward swinging of the stair structure after the panel is opened.

12. A disappearing stairway for cooperation with a ceiling opening comprising a stair structure, means pivotally and slidably mounting said stair structure at one end of the ceiling opening, locking means for releasably locking the stair structure against sliding on its mounting means, said locking means being adapted to be released and relocked by reciprocating movement of the stair structure, said stair structure being slightly overbalanced so as normally to be urged upwardly when the stair structure is locked on its mounting means, yielding means for resisting downward swinging of the stair structure after it has been released and moved to a point where the lower portion of the stair structure overbalances the upper portion thereof, a closure panel hinged to the side of the ceiling opening, and toggle linkage connecting said closure panel and said mounting means.

13. A disappearing stairway for cooperation with a ceiling opening comprising a stair structure, means pivotally and slidably mounting said stair structure at one end of the ceiling opening, locking means for releasably locking the stair structure against sliding on its mounting means, said stair structure being slightly overbalanced so as normally to be urged upwardly when the stair structure is locked on its mounting means, a closure panel hinged to the side of the ceiling opening, and a toggle linkage connecting said closure panel and said mounting means.
14. The combination with a disappearing stairway movable between a retracted position above a ceiling opening and a position of use in which it is extended from one end of the opening to a lower floor of a closure panel for said opening hinged at a side of said opening and operably associated with the stairway.
15. A disappearing stairway for cooperating with a ceiling opening between lower and upper floors, comprising a stair structure, a support for the stair structure adapted to pivotally and slidably mount such stair structure at one end of the ceiling opening whereby such stair structure is movable to an extended position in cooperation with the lower floor and to a retracted position on said support in which its upper portion overbalances by its weight alone the lower portion of the stairway and the support to move to and hold the stairway in a retracted position, and yielding means connected only to the stair structure to counterbalance the effect of the weight of the stair structure longitudinally whereof when extended.
16. A disappearing stairway for cooperation with a ceiling opening between lower and upper floors, comprising a stair structure, a support pivotally secured to the end of the ceiling opening and slidably and pivotally supporting said stair structure, a closure panel hinged to the side of said ceiling opening at the lower side thereof, swivelled toggle linkage connecting said closure panel and said support whereby when the stair is operated from below, downward movement of the panel will tip the support and the stair structure downwardly, and means on said panel cooperating with said stair structure to move said panel downwardly upon operation of the stair from above.
17. A disappearing stairway for cooperation with a ceiling opening between lower and upper floors, comprising a stair structure, a support pivotally secured to the end of the ceiling opening and slidably and pivotally supporting said stair structure, a closure panel hinged to the side of said ceiling opening at the lower side thereof, and swivelled toggle linkage connecting said closure panel and said support whereby when the

stair is operated from below, downward movement of the panel will tip the support and the stair structure downwardly.

18. A disappearing stairway for cooperation with a ceiling opening between lower and upper floors, comprising a stair structure, a support pivotally secured to the end of the ceiling opening and slidably and pivotally supporting said stair structure, a closure panel hinged to the side of said ceiling opening at the lower side thereof, and means on said panel cooperating with said stair structure to move said panel downwardly upon operation of the stair from above.
